UNITED STATES PATENT OFFICE.

ROBERT S. RILEY, OF WORCESTER, MASSACHUSETTS, ASSIGNOR TO RILEY STOKER CORPORATION, OF WORCESTER, MASSACHUSETTS, A CORPORATION OF MASSACHUSETTS.

DUMPING MECHANISM FOR MECHANICAL STOKERS.

Application filed January 23, 1924. Serial No. 688,063.

This invention relates to a mechanical stoker and particularly to mechanism for supporting and discharging the ash and refuse thereof. My invention is particularly applicable to an underfeed stoker and has for its general object the prevention of discharge or rearward movement of the fuel from the retorts during the discharge of refuse from the dumping plates.

10 In the preferred construction, the stoker is provided with pivotally mounted movable overfeed grates at the rear ends of the retorts, said grates preferably having a normal reciprocating movement with the retort 15 side walls and receiving also an upward displacement as the dumping plates are swung downward.

My invention further relates to the provision of improved mechanism for attaining this desired result, together with other arrangements and combinations of parts which will be hereinafter described and more particularly pointed out in the appended claims.

25 A preferred form of the invention is shown in the drawings, in which

Fig. 1 is a plan view of a portion of an underfeed stoker and its associated dumping plates;

30 Fig. 2 is a partial sectional elevation of the stoker, taken along the line 2-2 in Fig. 1;

Fig. 3 is a plan view of one of the dumping plates; and

35 Fig. 4 is a partial sectional elevation of a modification.

Referring to the drawings, I have indicated certain parts of an underfeed stoker including a retort bottom plate 10 and retort side walls 11, each supporting a series 40 or tuyère plates 12. A series of overfeed grates 13 are pivotally connected to the rear portions of the retort side walls 11 and are movable forward and rearward therewith.

45 The mechanism for moving the retort walls is not shown therein but may be similar to that shown in applicant's prior Patent No. 1,090,651.

The grates 13 are preferably of hollow 50 construction, providing an air space 14 in each grate which receives air from a chamber 15 which extends transversely across the stoker. The chamber 15 receives air through a passage 16 from a main air cham-

ber 17, and a damper 18 between the chambers 15 and 17 permits regulation of the air pressure in the chamber 15.

The fuel supporting face of each grate 13 is preferably formed in a series of steps, with interposed air passages through which air from the chamber 15 is delivered to the fuel on the overfeed grates. Lugs or projections 20 are secured to the lower sides of the grates 13 and rest upon the upper surfaces of dumping plates 21.

The dumping plates 21 are secured to a shaft 22 which extends transversely across the stoker and is supported in rigid bearings 23. Each dumping plate 21 is preferably provided with one or more depending cam plates 24, each of which engages a roller 25 at the rear end of a rack bar 26. The bars 26 are mounted to slide in bearings in the frame of the stoker and they are engaged by pinions 27 on a shaft 28 extending transversely of the stoker. By manual movement of the shaft 28, the racks 26 may be moved forward or rearward and the dumping plates may be thus moved from the full line position shown in Fig. 2 to the dotted line 80 position therein.

The upper surface of each dumping plate 21 extends forward beyond the axis of the shaft 22, as clearly indicated in Fig. 2. With this construction, it will be evident that each dumping plate 21, as it is swung downward, acts as a cam against one or more of the projections 20 to raise the overfeed grates 13 to the dotted line position shown in Fig. 2.

Such upward movement of the overfeed grates is effective to prevent rearward movement or discharge of the fuel from the retorts over the grates 13 while the dumping plates are lowered. It is thus possible to remove the ash and refuse from the dumping plates without at the same time causing a loss of good fuel which might otherwise escape over the grates 13.

It is sometimes desirable that the grates 100 13 should receive a slight angular movement during the operation of the stoker, in addition to the forward and rearward reciprocating movement thereof. When such angular movement is desired, it may be readily 105 obtained by positioning the dumping plates 21 at a slight angle either above or below the horizontal. In either case, the grates 13, as

they reciprocate, will be slightly raised and lowered by their sliding contact with the inclined surface of the dumping plates, giving a slight additional agitation of the fuel 5 at the rear of the retort.

The plates 21 may be provided with slots or openings 31 in the rear portion thereof through which air from the ash pit may work upward through the refuse to assist in 10 consuming any combustible material remaining therein.

In Fig. 4, I have shown a modified structure in which dumping plates 35 are provided with cam portions 36 supporting the 15 grates 37. As the grates are moved forward and rearward, the cam portions 36 supply vertical components of movement, and when swung downward to dumping position the grates are raised to hold the fuel as in the 20 form previously described.

Having thus described my invention and the advantages thereof, it will be seen that I have provided an extremely simple construction by which rearward movement of the 25 fuel over the grates 13 is automatically prevented during the dumping of the plates 21, and by means of which supplemental agitation of the fuel may be obtained if desired. It will also be evident that changes and 30 modifications can be made in my invention by those skilled in the art within the spirit and scope of my invention as set forth in the claims, and I do not wish to be otherwise limited to the details herein disclosed but—

35 What I claim is:—

1. In a stoker, a movably mounted overfeed grate, a dumping plate, and means to move said dumping plate, said dumping plate directly engaging said grate and thereby raising said grate by direct action thereof to prevent discharge of fuel over said grate when said dumping plate is lowered.

2. In a stoker, a plurality of retorts having side walls movable forwardly and rearwardly in said stoker, air-admitting overfeed grates mounted at the rear of said retorts and actuated to move forward and rearward with said walls, and dumping plates positioned at the rear of said overfeed grates, 45 said dumping plates engaging said grates to

and cooperating with said grates to give a vertical component of movement to said overfeed grates simultaneous with and in addition to said forward and rearward movement of said grates. 55

3. In a stoker, a plurality of retorts having movable side walls, grates pivotally mounted and connected to said movable walls to move therewith, dumping plates supporting the rearward ends of said grates, and means to dump said plates, said plates being formed to raise said grates as said plates are dumped, thereby preventing the discharge of fuel over said grates. 60

4. In a stoker, a plurality of retorts having movable side walls, grates pivotally mounted and connected to said movable walls to move therewith, dumping plates supporting the rearward ends of said grates, and means to dump said plates, said plates engaging portions of said grates and swinging said grates upward as said plates are lowered. 65

5. In a stoker, a plurality of retorts having side walls movable forwardly and rearwardly in said stoker, air-admitting overfeed grates mounted at the rear of said retorts and actuated to move forward and rearward with said walls, dumping plates positioned at the rear of said overfeed grates, said dumping plates engaging said grates to give a vertical component of movement to said overfeed grates simultaneous with and in addition to said forward and rearward movement of said grates, and means to change the angular position of rest of said dumping plates, thereby varying the extent of vertical movement of said grates. 70 75

6. In a stoker, a retort, an overfeed grate mounted at the rear of said retort, means to reciprocate said grate forward and rearward in said stoker, a dumping plate, and means to move said dumping plate to raised and lowered positions, said plate having a cam portion supporting the rear part of said grate and imparting additional movements to said grate as said grate is reciprocated. 80 85 90

In testimony whereof I have hereunto affixed my signature.

ROBERT S. RILEY.
